UNITED STATES PATENT OFFICE.

HENRY R. WARDELL, OF DAYTONA, FLORIDA, ASSIGNOR TO JOHNS-MANVILLE INCORPORATED, A CORPORATION OF NEW YORK.

SHINGLE FASTENING.

Application filed November 3, 1925. Serial No. 68,524.

This invention relates generally to roof coverings of the shingle type but is particularly applicable to flexible shingles, which are usually made by impregnating a somewhat flexible fabric, such as asbestos felt, with asphaltum or other hydro-carbon and with or without a surface coating of granular mineral material. More especially the invention is designed to be embodied in a shingle roof of this type in which substantially square shingles are laid in courses with their diagonal dimensions in horizontal and vertical planes, thereby producing a "pointed shingle" effect.

In roof coverings of the last above mentioned type, it is important to securely fasten the downwardly extending point or extremity of each shingle to prevent the same being curled upward by the wind or by unequal contraction and expansion in the body of the shingle, and also, as each such lower portion of one shingle extends out beyond the edges of the shingles of the next lower course, to supply a proper foundation over which said shingle may be fastened without bending or breaking it down over the edges of said shingles of the next lower course.

This invention secures these desirable results by placing under such lower portion of each shingle a reversed triangular portion of the shingle itself forming a flap, (which, of course, is of the same thickness as the adjacent shingles of the next lower course between which it will rest), and then providing a dart-shaped metal extension for said flap which will have lateral pointed extensions on its head, which extensions can be slipped under the adjacent shingles of the next lower course when a series of such shingles have been nailed to a roof deck in the usual way.

The best form of apparatus at present known to me embodying this invention is illustrated in the accompanying sheet of drawings in which:

Fig. 1 is a plan view of one side of the shingles to which my invention is to be applied, before bending the flap.

Fig. 2 is a detail bottom view of a portion of the shingle on an enlarged scale showing the flap and attached metal plate bent over into operative position.

Fig. 3 is a plan view of several courses of such shingles as applied to a roof and fastened thereon, parts being broken away.

Fig. 4 is a detail cross section on an enlarged scale taken on the line 4-4 of Fig. 5.

Fig. 5 is a detail perspective view of the metal plate.

Throughout the drawings like reference characters indicate like parts. 1 is a square shingle of the flexible type, the lower corner 2 of which has been creased along the line 2^a to permit the flap so formed to be bent back on and under the main body of the shingle. 3 is a dart-shaped piece of stiff material, such as a thin metal plate which has a base line 3^a substantially equal in length to the line of the crease 2^a, but which is otherwise quadrangular in shape. The dart shape may be produced by simply notching one corner of a square metal plate.

Plate 3 is fastened to the upper edge of flap 2 in any convenient way, as by staples, 3^b, 3^c, which are driven through the edge of flap 2, and then bent back on it. When flap 2 is folded under, preparatory to becoming a part of a roof structure, the plate 3 is then, of course, on the outer side of said flap.

When such shingles are applied to a roof deck 5, with the flaps at their lower corners, each course of shingles 1, 1, slightly overlapping, the next lower course 1^a, 1^a, and this second course overlaps a third lower course 1^b, 1^b, and so on. The shingles of each course are laid side by side with their laterally extending corners adjacent to one another and are preferably lapped over the next lower course far enough so that the lower edge, or line 2^a on which flap 2 has been bent, sub-tends at the angle formed by the adjacent edges of the shingles 2^a, 2^a of the next course beneath it. The triangular flap 2 is thus caused to fill the vertex of the angle formed by the adjacent edges of two lower shingles 1^a, 1^a, with the metal plate 3, having its edge portions 4, 4, projecting and slipped under said shingles of the lower course.

It is understood of course that the shingles may be nailed to the roof deck in any desired manner, not shown, the nails for each shingle preferably, of course, being so located that they will be covered by the shingles of the next upper course.

Obviously various stiff materials could be used to form plate 3, other than metal sheeting, so long as those plates are adapted to slip under the next lower course of shingles and to form extensions along the edges of flap 2, which constitute one element of a

composite fastening means, the other element of which is supplied by flap 2 serving as a base attachment to the main body of shingle 1. Also as is not always essential to fasten 5 the plate 3 on the particular side of flap 2 on which I have shown it in the drawings.

Obviously also, modifications might be made in the arrangement of the shingles of the various courses to produce a greater 10 or less amount of overlap or a different visual effect in the completed roof so long as the principles of the invention above described are retained.

The advantages of the invention comprise, 15 among other things, its simplicity, ease of application, security of fastening and economy of material. The triangular flap portion 2 forms a foundation having its upper surfaces in the plane of the upper surfaces 20 of the shingles of the next lower course so that the shingle to which it is attached will not bend downwards under any vertical pressure applied to it after it is in position. Consequently there is no tendency to flex 25 and break the shingles at any point after it is in position for use. Also the triangular flap portion 2 fits closely into and fills the triangular space existing below the lower portion of each shingle and between the adjacent edges of the shingles of the next lower course 1, and so prevents rain from being driven up into this cavity, or the collection therein of foreign matter which might tend to soften or rot the shingles 30 above and beneath and on either side of, such cavity.

The dart shape, or wedge outline, of plate 3 is important because it facilitates the insertion of the plate under the edges of the shingles of the next lower course, the pointed 40 tip 3c readily penetrating and easily dividing any mass of obstructive matter which may have been left under said shingles. This is especially helpful in patching an old roof by insertion of new shingles at 45 separate points.

Having described my invention, I claim:

A roof covering composed of pointed shingles comprising, in combination, a plurality of courses of substantially square shingles, 50 each course arranged with one set of the diagonal dimension of its constituent shingles horizontal and with the corners of adjacent shingles touching, each such course slightly overlapping the next lower course, 55 the lower corner of each shingle being bent under from exposed position and forming a flap placed under it in the vertex of the angle between two adjacent shingles of the next lower course, and a thin quadrangular plate of stiff material, having one corner clipped off to an extent such that the 60 cut edge approximates in length the line on which said flap is bent, fastened to said folded flap and extending beyond the point 65 and both sides of said flap and under said adjacent shingles of the next lower course; whereby said flap, and the lower portion of the shingle to which it is connected, are firmly anchored in position.

HENRY R. WARDELL.
